CONCRETE-FORM-CLAMPING APPARATUS

Application filed July 2, 1929. Serial No. 375,463.

This invention relates to improved adjustable clamping devices for locking form walls, used in pouring concrete, in operative assembled relation.

5 This invention has for its principal object to provide a novel construction and arrangement of means for adjustably mounting on the form-wall retaining bars tightening wedge devices adapted to line up and lock said retaining bars in holding relation to the form walls. To this end the tightening wedge devices include a wedge carrier, having means to receive an end of a retaining bar, and means to lock said carrier against 10 displacement from its initial adjusted position on the retaining bar, together with a wedge movably related to said carrier but normally non-separable therefrom.

This invention has for further objects the 20 provision of improvements in the structure whereby the wedge is movably related to its carrier, and whereby a firm bearing support for the operative end of the wedge is provided as a part of the carrier; and the provision of 25 a construction of wedge carriers and associated wedges which may be conjointly used in pairs to mutually support each other in producing the desired tightening stresses on the retaining bars, or which may be used 30 singly in conjunction with a wedge abutment block; all whereby the retaining bars may be squarely and tightly set up in holding relation to the assembled form walls about which they extend.

35 Other objects of this invention, having to do with more detailed improvements in the structure and design of the novel wedge carriers and associated wedges, and not at this time more particularly enumerated, will be 40 well understood from the following detailed description of the same.

Illustrative embodiments of this invention are shown in the accompanying drawings, in which:

45 Fig. 1 is a plan view showing the novel wedge carriers and associated wedges mounted on overlapping retaining bars and arranged in pairs, the members of which mutually cooperate to provide thrust abutments 50 for the wedges, all arranged in holding rela-

tion to assembled form walls; Fig. 2 is a fragmentary edge elevation, on an enlarged scale, viewed in the direction of the arrow *x* in Fig. 1; Fig. 3 is an enlarged plan view of a carrier and its associated wedge as mounted on the end of a retaining bar; Fig. 4 is a transverse section, taken on line 4—4 in Fig. 3; and Fig. 5 is a longitudinal section, taken on line 5—5 in Fig. 3.

55 Fig. 6 is a view similar to that shown in Fig. 1, but with the carriers and wedges used singly in conjunction with wedge abutment blocks; and Fig. 7 is a fragmentary sectional view, taken on line 7—7, in Fig. 6.

60 Fig. 8 is a plan view of a carrier and its wedge showing a modified means for fixing the carrier in desired adjusted position on a retaining bar; Fig. 9 is a similar view showing another arrangement for fixing the carrier in desired adjusted position on a retaining bar; and Fig. 10 is a plan view of a carrier and its wedge showing a modified means for retaining the wedge thereof against disassembly therefrom.

65 Similar characters of reference are employed in all the hereinabove described views, to indicate corresponding parts.

70 Referring to the drawings, the reference character 11 indicates one set of form walls and 12 the other set of form walls which are 75 arranged at right angles to the walls 10, so as to provide a mold or form of rectangular section, such as is employed in pouring concrete piers, columns and similar structures.

80 The form clamping apparatus, according to this invention, comprises retaining bars 13, 14, 15 and 16 of lengths exceeding the lateral dimensions of the form, the same being 85 adapted to be disposed respectively around the respective form walls, with their adjacent intersecting ends overlapping. Adjacent overlapping ends of the retaining bars 13—14 are suitably secured together by any suitable 90 means adapted to retain the same from separation at such points. Illustrative of one 95 method of so securing said bars, I have shown, in Fig. 1, the ends of the bars provided with perforations 17, so that a perforation of one bar may be registered with a perforation of 100 the other bar, and thereupon a holding pin

or the like 18 passed therethrough to thus secure the bars against relative displacement. In like manner, adjacent overlapping ends of the retaining bars 15—16 are secured together by registered perforations 17 through which are passed a holding pin 18.

With the retaining bars arranged as above set forth, the free ends of the bars 13—16 will overlap in intersecting relation, and on these 10 free ends are then disposed the wedge carriers and wedges of the clamping devices.

Each clamping device comprises a wedge carrier consisting in a main body 19 longitudinally apertured to provide a passage 20 therethrough to receive a retaining bar whereby the wedge carrier is adjustably movable on the latter. Connected with the inner side of said main body 19 is a laterally projecting boss or neck 21, through which 20 extends an internally threaded opening 22 terminating at its inner end in communication with the passage 20. Threaded into said opening 22 is a set screw 23 which may be tightened to bind against a side of the retaining bar to thus hold the main body 19 in locked adjusted position on the latter. Integrally formed with the outer side portion of the main body 19 is a longitudinal portion arranged so as to form the outer side 30 wall 24 of the passage 20, and extending longitudinally forward beyond the inner end of the main body 19, so as to lie against the outer edge of a retaining bar extending through said body 19, thereby also forming a 35 wedge bearing 24'. Extending laterally beyond the outer side portion of the main body 19 are spaced wing-plates 25 to provide a supporting slideway for an adjustable wedge member 26, which is disposed to extend 40 through the slideway with its straight edge slidably bearing on the side wall 24 and wedge bearing 24', and with its oblique edge outward. In order to retain said wedge member 26 in the described assembled relation to the carrier, and yet free for longitudinal movement, cooperative male and female keeper means are provided. In one form, the female keeper means, which is provided in the wedge body, comprises a de- 45 pressed longitudinal channel or groove 27 which is counter-sunk in a face of the wedge, and the male keeper means, which is provided in connection with the carrier, comprises a tongue or lug 28 struck downwardly 50 out of the overlying wing-plate 25, so that its free end engages in said channel or groove 27. It will be obvious that the interengagement of the described male and female parts will retain the wedge against separation from 55 the carrier, while nevertheless permitting adequate longitudinal movement of the same.

A modified construction and arrangement of cooperative male and female keeper means for retaining a wedge in assembled relation 60 to its carrier is shown in Fig. 10, wherein

the wedge member 26 is cut away along a portion of its outer side to provide a longitudinally indented marginal way 29, and wherein the outer marginal free end portion of wing-plate 25 is bent over to provide lip 70 30 entered in said way 29 of the wedge. This arrangement likewise retains the wedge against separation from the carrier, while nevertheless permitting adequate longitudinal movement thereof.

Extending longitudinally of the wedge member 26 is a row of spaced perforations 31, for purposes subsequently mentioned.

Integrally connected with the inner end of the main body 19 of the carrier is a horizontally off-set clip-member 32, which, when the carrier is placed upon a retaining bar, provides a receiving space in which may be engaged a portion of overlapping retaining bar, so that the thus associated bars are held against separation in vertical plane one from the other.

In applying the clamping devices to overlapping free end portions of retaining bars so that the former are related in mutually cooperative relation, as shown in Fig. 1, and, for example, as applied to the bars 13—16 in said Fig. 1, the body member 19 of one clamping device is engaged over the end of the bar 16 and the body member 19 of the other 90 clamping device, in reversed position, is engaged over the end of the bar 13. The clamping devices are then moved or slid inwardly on the respective bars so that the wedge 26 of one will abut against the body 19 of the other, said wedges being each drawn outward to an initial non-wedging position. As thus arranged the wedges will respectively lie in overlapping planes and in intersecting relation. This preliminary positioning of the clamping devices is effected while the set-screws 23 are relaxed, and may be rapidly and easily accomplished since the main bodies 19 are then freely slidable on their respective bars 13—16. When the clamping devices have been thus positioned, the set-screws 23 are tightened, thus locking the main bodies against displacing movement relative to the bars on which they are respectively mounted. An advantage of the 105 structure, having the set-screw form of locking means, is that the preliminary positioning of the clamping devices may be such as to bring all the parts of the latter into snug cooperative relation even with the wedges 26 110 drawn to their outward limit of movement or fully relaxed, and consequently the maximum tightening effect of the wedges, when the same are driven home is obtainable, without loss of a portion of the wedge thrust 115 required to take up initial slack between the cooperating clamping devices.

When the clamping devices have been set up and locked in initial cooperative relation, the wedges 26 are driven inwardly, whereby 120

the wedge on the clamping device mounted on the bar 13 thrusts outwardly on the clamping device on the bar 16, and vice versa, thus drawing the bars tightly around the form.

It will be understood that a pair of clamping devices mutually cooperative in the manner above described are also mounted on the free overlapping ends of the bars 14 and 15, and that the same will be diagonally opposed to the first mentioned set of clamping devices; consequently when both sets are tightened up by manipulating their wedges the effect will be to draw or contract all the bars into a form and tight encircling or embracing relation to the form walls.

After the wedges of the clamping devices are driven home they may be locked against relaxation in any suitable manner, for example, either by passing a lock-pin 33 through holes in the wing plates 25 and through a registered perforation 31 of the wedge, or by passing such a lock pin 33 through registered perforations 31 positioned at the intersection of said wedges.

Preferably each wedge 26 is provided at its outer or rearward end with an enlarged head portion 34, the inner shoulder of which forms a stop which, on abutting a portion of the main body member of the carrier to which it is attached, serves to limit the inward movement of the wedge. Additionally said head portion 34 provides an enlarged portion well calculated to receive and withstand the blows administered to the wedge, when driving the latter home to desired tightening position.

Attention may here be called to the fact that means other than a set screw may be utilized to lock the main body 19 of the carrier to the bar upon which it is mounted. For example, as shown in Fig. 8, the bar may be provided on its outer edge with spaced marginal notches 35, and the free end of the bearing member 24', which abuts the outer edge of the bar, may be provided with an inwardly projected spur or lug 36. The passage 20 of the body 19 of the carrier, in this case, is made of a width exceeding that of the bar, so that lateral play of the body relative to the bar is possible, sufficient to permit disengagement of the spur or lug 36 from a notch 35, so that longitudinal adjustment of the body 19 on the bar may be attained and selective engagement of the spur or lug 36 with a given notch 35, according to the required disposal of the body in initial set up position on the bar. Again, for example, as shown in Fig. 9, another form of carrier locking means may be utilized, the same comprising the provision in the bar of longitudinally spaced perforations 37, with aligned perforations in the horizontal walls of the body passage 20 with which selected perforation 37 may be registered so that a holding pin 38 may be passed through the parts to

retain the same against relative movement.

In Figs. 6 and 7 I have shown the novel clamping devices arranged in single unit relation at each corner of a form and in cooperative relation with a wedge abutment block. The form, in such case, may comprise the walls 11 and 12, and the retaining bars 13, 14, 15 and 16 are employed to extend around or embrace the form walls. A single clamping device comprising the wedge carrier and its associated wedge is mounted on an end of the bar 16 adjacent to the point where the latter overlaps and intersects an end of the bar 13, and the clamping device is locked on the bar 16 in initial holding position. Mounted on the adjacent end of the bar 13 is an abutment block 39, the latter having a longitudinal passage through which the bar 13 extends, and a set-screw 40 laterally threaded thereinto to fix the abutment block 39 in operative position. The inner end of the abutment block 39 has an oblique portion 41 corresponding to the angle of inclination of the outer margin of the wedge 26. In practice, after the carrier is fixed on the bar 16 and its wedge member 26 outwardly withdrawn to relaxed position, the abutment block 39 is slid up on the bar 13 until its oblique portion 41 engages the wedge member 26, whereupon the abutment block is secured against displacement by screwing home the set-screw 40. A carrier and associated wedge with cooperating abutment block 39 is fixed, in like manner, to the overlapping and intersecting ends of the bars 13 and 14, 14 and 15, and 15 and 16, thus providing a clamping structure at each corner of the form. When the clamping devices are thus initially set up, the respective wedge members 26 may be driven inward, to thereby contract the bars about the form walls and into tight holding relation thereto. The wedge members are then locked against relaxation by passing holding pins 33 through the wing plates 25 of the wedge carriers and through a perforation 31 of the wedge, as already above explained.

In the novel construction of wedge carrier and associated wedge, the provision in connection with the former of the wedge bearing portion 24' is of considerable advantage; first, for the reason that it permits the body member 19 of the carrier to entirely embrace or encircle the bar on which it is mounted, and, second, because it provides a straight and true bearing support against which the wedge may slide, and thus avoids necessity for moving the wedge in contact with rough or batter edges of the bars per se.

I am aware that some changes, other than those above mentioned, may be made in the general arrangements and combinations of the various devices and parts, as well as in the details of the construction of the same, without departing from the scope of this invention.

as described in the foregoing specification, and as defined in the appended claims. Hence, I do not limit my invention to the exact arrangements and combinations of the several devices and parts as set forth in the foregoing specification, nor do I confine myself to the exact details of the construction of said parts as illustrated in the accompanying drawings.

10 I claim:—

1. In a form clamping apparatus having retaining bars to girdle the form with their adjacent end portions in overlapped relation, wedge carriers each comprising a main body having a passage therethrough to receive a retaining bar end portion, means for fixing said main body against movement on the bar, a clip on said main body to engage over the adjacent overlapping bar, said main body including a wedge bearing portion extending along an edge of the bar on which said main body is mounted, a wedge slidably disposed against said bearing portion, means for retaining said wedge in assembled relation to said main body but free for wedging movement, and means on an adjacent overlapping retaining bar against which said wedge may thrust.

2. In form clamping apparatus having retaining bars to girdle the form with their adjacent end portions in overlapped relation, wedge carriers each comprising a main body having a passage therethrough to receive a retaining bar end portion, means for fixing said main body against movement on the bar, a clip on said main body to engage over the adjacent overlapping bar, said main body including a wedge bearing portion extending along an edge of the bar on which said main body is mounted, a wedge slidably disposed against said bearing portion, means for retaining said wedge in assembled relation to said main body but free for wedging movement, and means on an adjacent overlapping retaining bar against which said wedge may thrust, and means for retaining a tightened wedge against relaxation.

3. In a form clamping apparatus, retaining bars to girdle the form with their adjacent end portions in overlapped relation, means for securing certain overlapping end portions of said retaining bars together, wedge carriers engageable in mutually cooperative relation on remaining overlapping end portions of said retaining bars, each wedge carrier comprising a main body having a passage therethrough to receive a retaining bar end portion, means for fixing said main body against movement on the bar, a clip on said main body to engage over the adjacent overlapping bar, said main body further including a wedge bearing portion extending along an edge of the bar on which said main body is mounted, a wedge slidably disposed against said bearing portion, and means for retaining

said wedge in assembled relation to said main body but free for wedging movement, said wedge carriers on adjacent overlapping retaining bar end portions being cooperatively associated whereby the wedge of one thrusts 70 against the main body of the other.

4. In a form clamping apparatus, retaining bars to girdle the form with their adjacent end portions in overlapped relation, means for securing certain overlapping end 75 portions of said retaining bars together, wedge carriers engageable in mutually cooperative relation on remaining overlapping end portions of said retaining bars, each wedge carrier comprising a main body having a passage therethrough to receive a retaining bar end portion, means for fixing said main body against movement on the bar, a clip on said main body to engage over the adjacent overlapping bar, said main body further including a wedge bearing portion extending along an edge of the bar on which said main body is mounted, a wedge slidably disposed against said bearing portion, means for retaining said wedge in assembled relation to 85 said main body but free for wedging movement, said wedge carriers on adjacent overlapping retaining bar end portions being cooperatively associated whereby the wedge of one thrusts 90 against the main body of the other, and means for retaining said wedges when tightened against relaxation.

5. In a form clamping apparatus, retaining bars to girdle the form with their adjacent end portions in overlapped relation, means for securing certain overlapping end portions of said retaining bars together, wedge carriers engageable in mutually cooperative relation on remaining overlapping end portions of said retaining bars, each wedge carrier comprising a main body having a passage therethrough to receive a retaining bar end portion, a set screw threaded through one side of said main body engageable with the bar to lock said main body against movement thereon, a clip on said main body to engage over the adjacent overlapping bar, said main body further including at its opposite side a wedge bearing portion extending along an edge of the bar on which said main body is mounted, a wedge slidably disposed against said bearing portion, and means for retaining said wedge in assembled relation to said main body but free for wedging movement, said wedge carriers on adjacent overlapping retaining bar end portions being cooperatively associated whereby the wedge of one thrusts 105 against the main body of the other.

6. In a form clamping apparatus, retaining bars to girdle the form with their adjacent end portions in overlapped relation, means for securing certain overlapping end portions of said retaining bars together, wedge carriers engageable in mutually cooperative relation on remaining overlapping end portions 110

of said retaining bars, each wedge carrier comprising a main body having a passage therethrough to receive a retaining bar end portion, a set screw threaded through one side of said main body engageable with the bar to lock said main body against movement thereon, a clip on said main body to engage over the adjacent overlapping bar, said main body further including at its opposite side a wedge bearing portion extending along an edge of the bar on which said main body is mounted, a wedge slidably disposed against said bearing portion, means for retaining said wedge in assembled relation to said main body but free for wedging movement, said wedge carriers on adjacent overlapping retaining bar end portions being cooperatively associated whereby the wedge of one thrusts against the main body of the other, and means for retaining said wedges when tightened against relaxation.

7. A wedge carrier for engagement on retaining bars of form clamping apparatus, comprising a main body having a passage therethrough to receive a bar, means for fixing said main body against movement of the bar, a wedge bearing portion connected with said main body to extend along an edge of the bar, a wedge slidably disposed against said bearing portion, means for retaining said wedge in assembled relation to said main body but free for wedging movement, and said main body further including an off-set clip to engage a bar overlapping said first mentioned bar.

8. A wedge carrier for engagement on retaining bars of form clamping apparatus, comprising a main body having a passage therethrough to receive a bar, a wedge bearing portion at one side of said main body to extend along an edge of the bar, wedge supporting means laterally projecting beyond said bearing portion, a wedge slidably mounted in said supporting means and slidably disposed against said bearing portion, said supporting means and wedge having cooperative male and female means to retain said wedge in assembled relation to said main body but free for wedging movement, and means for fixing said main body against movement on the bar.

9. A wedge carrier for engagement on retaining bars of form clamping apparatus, comprising a main body having a passage therethrough to receive a bar, a wedge bearing portion at one side of said main body to extend along an edge of the bar, wedge supporting means laterally projecting beyond said bearing portion, a wedge slidably mounted in said supporting means and slidably disposed against said bearing portion, said supporting means and wedge having cooperative male and female means to retain said wedge in assembled relation to said main body but free for wedging movement, means for fixing

said main body against movement on the bar, and said main body further including an off-set clip to engage a bar overlapping said first mentioned bar.

10. A wedge carrier for engagement on retaining bars of form clamping apparatus, comprising a main body having a passage therethrough to receive a bar, a set screw threaded through one side of said main body engageable with said bar to lock said main body against movement thereon, a wedge bearing portion at the opposite side of said main body to extend along an edge of the bar, wedge supporting means laterally projecting beyond said bearing portion, a wedge slidably mounted in said supporting means and slidably disposed against said bearing portion, said supporting means and wedge having cooperative male and female means to retain said wedge in assembled relation to said main body but free for wedging movement, and said main body further including an off-set clip to engage a bar overlapping said first mentioned bar.

In testimony, that I claim the invention set forth above I have hereunto set my hand this 29th day of June, 1929.

SAMUEL S. COLT.
